UNITED STATES PATENT OFFICE

NORMAN V. CHRISTENSEN, OF CHICAGO, ILLINOIS, ASSIGNOR TO UNION SPECIAL
MACHINE COMPANY, OF CHICAGO, ILLINOIS, A CORPORATION OF ILLINOIS

PRESSER FOOT FOR SEWING MACHINES

Application filed June 23, 1927. Serial No. 202,090.

The invention relates to new and useful improvements in a presser foot for sewing machines, and more particularly to a presser foot for felling.

5 An object of the invention is to provide a presser foot having a channel extending lengthwise thereof for guiding the fabric sections for felling, with means whereby said presser foot exerts a uniform pressure on the 10 interfolded portions of the fabric in the region directly in rear of the needles and extending throughout the entire length of the feed dog section in rear of the needles, and whereby said presser foot exerts a yielding 15 clamping action upon the enchainied thread loops directly in rear of the needles during chaining off.

A further object of the invention is to provide a presser foot of the above type wherein 20 yielding fingers are provided in the channel for guiding the interfolded fabric sections for clamping the enchainied thread loops during chaining off, and wherein adjustable stops are provided for limiting the movement of 25 said adjustable fingers in an upward direction during felling, so as to exert a uniform pressure on said interfolded portions of the fabric throughout the entire length of the fingers.

30 A further object of the invention is to provide a presser foot of the above type wherein the foot portion is pivoted to a supporting shank so that the foot portion may tilt to receive the fabric sections and also tilt when the fabric sections of a stitched article are 35 passing from beneath the foot, and wherein positive means is provided for limiting the tilting movement of the foot in both directions.

40 These and other objects will in part be obvious and will in part be hereinafter more fully disclosed.

In the drawings which show by way of 45 illustration one embodiment of the presser foot—

Figure 1 is a side view of the same;

Fig. 2 is a view showing the presser bar in section, and the presser foot in plan; 50 Fig. 3 is a sectional view on the line 3, 3 of

Fig. 2, and showing the needle and feed with the parts positioned during chaining off;

Fig. 3^a is a view similar to Fig. 3, but showing the position of the parts during felling;

Fig. 4 is a sectional view on the line 4, 4 of 55 Fig. 1.

In the application of Joseph Berger, Serial No. 121,425, filed July 9, 1926, there is shown and described a presser foot for felling having chaining fingers for engaging the enchainied thread loops in rear of the needles, and also having a channel for guiding the interfolded portions of the fabric sections which are being stitched together. The present invention is directed to an improvement upon the presser foot of said application. The presser foot includes a shank portion 1 which is mounted on a presser bar 2 of the usual type. Said shank portion 1 extends the full width of the foot portion and is provided with recesses 4, 4 adjacent the sides thereof. The foot portion is provided with upstanding members 5, 5 which fit within these recesses 4, 4, and a pivot rod 6 passing through the shank and the upstanding portions of the foot, pivotally secures the foot to the shank. The extreme side portions of the shank are beveled or cut away at 7 and 8. These cut away portions are for the purpose of providing proper clearance for the 70 swinging of the foot. The shank of the presser foot is recessed at 9 and a rod 10 carried by the foot portion extends across the same and is located in this recess. The rod 10 contacts with the walls of the recess and 75 limits the swinging movement of the presser foot on the shank.

The foot portion is provided with a channel 11. This channel extends clear to the front end of the foot and is of proper width 90 to receive the interfolded portions of the fabric sections which are to be united in the fell seam. This channel 11 extends all the way to the rear of the foot. Located in the channel are fingers 12, 13 and 14. Three 95 fingers are shown in the drawings, because the foot is designed to be used with three needles. If the foot was intended for a single needle machine, then of course, only one finger would be used. Any number of needles may 100

be used, and the foot will be constructed with a yielding finger for each needle. The presser foot is provided with a needle opening 15 for each needle, and the yielding finger 5 terminates at the rear side of this opening, and is preferably curved to form the rear side of the needle opening. Thus it is that each finger terminates directly in rear of the needle with which it is associated. When 10 the foot is adapted for a three needle machine, the needle openings are arranged in a line at an acute angle to the longitudinal axis of the foot. This is for the purpose of permitting an independent looper moving in a direction at right angles to the longitudinal axis of the foot to cooperate with each needle. 15

In Figures 3 and 3^a, one of the three needles is shown, and is indicated at 16. Cooperating with this needle is a looper 17. The material being stitched passes over a throat plate 18 and is fed beneath the presser foot by the feed dog 19. The throat plate 18 is provided with a solid portion 20 directly in rear of the opening in the throat plate for each needle. 25

Coming back again to the yielding fingers, the three yielding fingers are all pivotally mounted on the supporting bar 21. This pivotal supporting bar 21 is some distance in 30 rear of the pivotal support 6 for the foot portion of the presser foot. There is a spring 22 for each yielding finger. This spring bears against an adjustable screw 23 threaded into the upper end of the rear portion of the 35 finger. These yielding fingers, as to their mounting, and the springs for actuating the same, form no part per se of the present invention, but are shown, described and claimed in the application filed by Walter M. Hanne- 40 man and Russell H. Rideout, November 24, 1926, Serial No. 150,460.

The upstanding members 5, 5 are connected by the cross bar 24. Threaded into this cross bar are three adjustable stop screws 25, 25, 25. 45 There is a stop screw for each finger. These stop screws limit the upward movement of the forward end of the fingers.

The operation of the improved presser foot is as follows. In Fig. 3^a, the material is 50 shown as passing beneath the foot, the parts being interfolded to form a fell. The interfolded parts of the fabric sections are received and guided by the channel 11 at the forward end of the foot portion. The fingers 55 12, 13 and 14 rest on the upper face of the interfolded portions of the fabric sections. The main spring acting on the presser bar 2 will force the foot section downwardly. The front portions of the fingers will be pressed 60 upwardly by the fabric until the stop screws are engaged. The rear portions of the fingers pivot on the bar 21 and have no movement relative to the foot section at their pivotal centers, and therefore, these fingers, in effect, 65 become the solid portion of the foot section.

during the stitching of the fabric sections and the forming of the fell seam. The foot portion will tilt on the pivot bar 6 to permit the fabric sections to enter. The fingers will also tilt on the foot section as the stop screws 70 are carried thereby. This is during the enter- 75

ting of the fabric beneath the foot, as the fabric will engage the fingers, pass underneath the curved forward ends thereof, and swing the fingers until they engage the stops. The fingers, however, will not be brought into engagement with the stops, until the fabric passes underneath the fingers. Therefore, the springs 22 will swing the forward ends 80 of the fingers downward and cause the en- 85

chained thread loops between articles to be properly clamped for chaining off, and the feeding of the enchain- 90

ed thread loops. When the fabric sections are all the way beneath the foot, the yielding fingers will engage the upper face of the interfolded fabric sections with a uniform pressure throughout the entire length of the finger. The sections of the feed dog 19 directly beneath the fingers, will, therefore, have a cooperative action with the finger throughout the entire length of the section of the feed dog. During felling, when the fabric is entirely beneath the foot, the presser foot operates, in effect, as a solid 95

foot. When the fabric is starting beneath the foot, however, then the finger will yield and cooperate with the throat plate and feed in the chaining off, after the manner fully set forth in the Berger application. Likewise, when the article is leaving the foot, the 100

fingers will again cooperate with the throat plate and the feed dog in the insuring of the proper formation of the stitches and the chaining off between articles.

As has been noted above, the stops 25 are 105

adjustable, and this is particularly for the

purpose of adjusting the chaining fingers for

operating on fabrics of different thicknesses.

By adjusting these stops, the upward move- 110

ment of the chaining fingers can be varied so

as to bring about a substantially solid foot

condition for the thickness of fabric being

stitched.

It is obvious that minor changes in the de- 115

tails of construction can be made without de- 120

parting from the spirit of the invention as set

forth in the appended claims.

Having thus described the invention, what 125

I claim as new and desire to secure by Letters-

Patent, is—

1. A felling presser foot for sewing ma- 130

chines comprising a supporting shank, a foot

portion pivoted to said shank, said foot por- 135

tion having a needle opening therethrough,

and a channel in its under face at the forward

end thereof disposed so as to receive and

guide the interfolded portions of the fell

seam, said foot portion having means for en- 140

gaging the interfolded portions of the fabric

sections with a uniform pressure in rear of

the needles and from a point adjacent the needles to the rear of the foot during felling when the fabric sections are fully beneath the foot portion, and for yieldingly clamping and feeding the enchain'd thread loops between stitched articles and while the articles are entering beneath the foot and passing from beneath the foot.

2. A felling presser foot for sewing machines comprising a supporting shank, a foot portion pivoted to said shank, said foot portion having a needle opening therethrough and a channel in its under face at the forward end thereof disposed so as to receive and guide the interfolded portions of the fell seam, said foot portion having means for engaging the interfolded portions of the fabric sections with a uniform pressure in rear of the needles and from a point adjacent the needles to the rear of the foot during felling when the fabric sections are fully beneath the foot portion, and for yieldingly clamping and feeding the enchain'd thread loops between stitched articles and while the articles are entering beneath the foot and passing from beneath the foot.

3. A felling presser foot for sewing machines comprising a supporting shank, a foot portion pivoted to said shank, said foot portion having a needle opening therethrough and a channel in its under face at the forward end thereof disposed so as to receive and guide the interfolded portions of the fell seam, said foot portion having means for engaging the interfolded portions of the fabric sections with a uniform pressure in rear of the needles and from a point adjacent the needles to the rear of the foot during felling when the fabric sections are fully beneath the foot portion, and for yieldingly clamping and feeding the enchain'd thread loops between stitched articles and while the articles are entering beneath the foot and passing from beneath the foot, means for limiting the swinging movements of the foot portion on said shank when the fabric section is passing from beneath the foot, said pivotal connection between the foot portion and shank including spaced upwardly projecting members carried by the foot portion adapted to engage recesses in the shank, and a rod extending through said shank and upwardly projecting portions.

4. A felling presser foot for sewing machines comprising a supporting shank, a foot portion pivoted to said shank, said foot portion having a needle opening therethrough and a channel in its under face at the forward end thereof disposed so as to receive and

guide the interfolded portions of the fell seam, said foot portion having means for engaging the interfolded portions of the fabric sections with a uniform pressure in rear of the needles and from a point adjacent the needles to the rear of the foot during felling when the fabric sections are fully beneath the foot portion, and for yieldingly clamping and feeding the enchain'd thread loops between stitched articles and while the articles are entering beneath the foot and passing from beneath the foot, said pivotal connection between the foot portion and shank including spaced upwardly projecting members carried by the foot portion adapted to engage recesses in the shank, a rod extending through said shank and upwardly projecting portions, said shank at the outer sides thereof having directly beneath said pivot, beveled faces disposed in front and in rear of the pivot, and adapted to engage, respectively, the upper face of the foot portion for limiting its swinging movement.

5. A felling presser foot for sewing machines comprising a supporting shank, a foot portion pivoted to said shank, said foot portion having a needle opening therethrough and a channel in its under face at the forward end thereof disposed so as to receive and guide the interfolded portions of the fell seam, a finger located in the channel in rear of the needle opening and pivoted to the foot portion, a spring engaging the finger for normally depressing the forward portion thereof, an adjustable stop screw carried by the foot portion and limiting the upward movement of the finger, said finger being shaped and disposed so as to engage the interfolded portions of the fabric sections with a uniform pressure from a point in rear of the needle to the rear end of the foot, when the fabric sections are completely beneath the foot portion, and for yieldingly engaging and clamping the enchain'd thread loops against the throat plate and cooperating with the feed in the feeding of the enchain'd loops when an article is passing from beneath the foot between stitched articles, and when a new article to be stitched is entering beneath the foot.

6. A felling foot for sewing machines comprising a foot portion having a channel extending lengthwise thereof for guiding the interfolded portions of the fabric sections for felling, a finger located in the channel and pivoted to the foot portion adjacent the rear end of the foot, a spring engaging said finger and normally depressing the forward end thereof, a stop screw carried by the foot portion and engaging and limiting the upward movement of the forward end of said finger.

7. A felling presser foot for sewing machines comprising a foot portion having a channel extending lengthwise thereof for guiding the interfolded portions of the fabric

sections, a finger located in said channel and pivoted to the foot portion adjacent the rear end thereof, said finger terminating at the needle opening in the foot portion, a spring bearing against the finger for normally depressing the forward end thereof, and an adjustable stop screw carried by the foot portion and limiting the upward movement of the finger through the action of the fabric sections thereon.

8. A felling presser foot for sewing machines comprising a supporting shank, a foot portion having a needle opening therethrough and a channel in its under face disposed so as to receive and guide the interfolded portions of the fell seam, yielding devices carried by the foot portion for engaging the interfolded portions of the fabric sections when the fabric sections are fully beneath the foot portion and movable beneath the plane of the lower face of the presser foot when said foot is raised for yieldingly clamping and feeding the enchain'd thread loops between stitched articles while the articles are entering beneath the foot and passing from beneath the foot, and means for limiting the upward movement of said yielding devices whereby said devices are held in rigid relation to the remainder of the foot while felling the interfolded parts of the fabric.

In testimony whereof, I affix my signature.
NORMAN V. CHRISTENSEN.
